UNITED STATES PATENT OFFICE.

EMIL HOLTHAUSE, OF BROOKLYN, NEW YORK.

FEED-WATER HEATER AND PURIFIER.

SPECIFICATION forming part of Letters Patent No. 406,282, dated July 2, 1889.

Application filed March 23, 1889. Serial No. 304,566. (No model.)

To all whom it may concern:

Be it known that I, EMIL HOLTHAUSE, a citizen of the United States, residing at Brooklyn, Kings county, New York, have invented certain new and useful Improvements in Feed-Water Heaters and Purifiers, fully described and represented in the following specification and the accompanying drawings, forming a part of the same.

10 This invention is applicable particularly to horizontal boilers having return-flues, and the object of the invention is to furnish a simple and effective means of heating and purifying the feed-water of the boiler, and the operation 15 of which may be discontinued when desired.

The invention consists, first, in the combination, with the boiler and its casings, of a vertical flat coil of pipes connected with the feed-supply and arranged in the uptake-flue 20 at the rear end of the boiler, and a non-conducting envelope or shield suspended above the same through the boiler-casing and adapted when lowered to inclose the said coil of pipes to shield them from the heat.

25 It also consists in the combination, with the same parts, of a mud-drum connected with the bottom of the said coil, a filter connected with said mud-drum, and suitable means for cutting off the feed-water from the coil and 30 lowering the shield over the coil when it is desired to discontinue its use.

In the annexed drawings, Figure 1 is an elevation of the boiler having my improvement, with its casings in section. Fig. 2 is 35 an end elevation of the same with the boiler-casing removed to disclose more fully the construction and arrangements of the parts, and Fig. 3 is a horizontal section of the envelope on a larger scale.

40 A is the boiler; B, the metallic boiler-front used to sustain the front end of the boiler; C, the bridge-wall; D, the grates; E, the uptake at the rear of the boiler, and I the boiler-flues adapted to conduct the flame and smoke

45 to the front end of the boiler, whence they would be conducted to the chimney by a suitable breeching. The pipe-coil consists in a continuous series of pipes f, arranged over one another and connected by return-bends g 50 in such manner as to drain freely from the top to the bottom, and thus prevent the collection of sediment therein.

h is the water-supply pipe; j, a branch of the same extended horizontally over the uptake E to the filter k. The filter is shown 55 provided above the entering pipe j with previous diaphragms q and granular filling r, and the outlet-pipe is carried from the top of the granular filling; but the constructive features of the filter are wholly immaterial. 60

i is a vertical branch from the pipe j to the top of the coil.

The boiler-casing F is shown as a wall with an aperture G over the coil to permit the passage of a shield s', for the purpose set forth. 65 The brick-work above the coil is shown supported by a metal plate H; but a casing of any other suitable construction may be used. The lower end of the coil is connected with a mud-drum m, and the latter is connected by a 70 vertical pipe m' to the branch j. The pipes i and m' are arranged vertically in line with the ends of the coil to facilitate the application of the shield to the coil and the movement of the same vertically through the boiler-casing to expose the coil to the heat when 75 desired. Cocks l and l' are inserted in the pipes i and j, and a cock n in the pipe m'.

A delivery-pipe o is extended from the filter to the lower part of the boiler and provided 80 with a check-valve o', and the water may be caused to pass through the coil and the mud-drum before entering the filter by closing the cock l' and opening the cocks l and n, or the water may pass to the boiler without traversing the coil by opening the cock l' and closing the cocks l and n. The flame moving 85 through the uptake E passes between and around the pipes of the coil, and thus heats them in a high degree, and when the water is 90 passed through the same its impurities are precipitated and are in a great measure deposited in the mud-drum. The filter and mud-drum are both provided with pipes p and cocks p' to withdraw the sediment at intervals. 95

When the boiler requires no feed-water, it is obvious that the circulation would need to be cut off from the coil, and its contents would therefore soon become converted into steam 100 and the joints of the pipe would be injured. To protect the coil at such times, I provide the hollow shield, consisting in the inner jacket s and the outer jacket s', provided

with intermediate space t , having a bottom extending between such jackets, which would be filled with ashes, plaster, or other non-conducting and non-combustible material. The 5 inner jacket is shaped to loosely embrace the vertical pipes i and m' (which are shown in dotted lines in Fig. 3) and to slide vertically over such pipes and over the coil-pipes f and their return-bends g . The outer jacket 10 is made of similar shape, but large enough to form the intermediate space t , and each jacket is preferably formed of two halves provided with flanges u , clamped upon an intermediate plate v by bolts v' , by which construction the 15 shield is cheaply made and is rendered firm and rigid. Hooks a are attached to the top of the shield, and cords b are connected therewith and are carried over guide-pulleys a' , mounted upon any suitable supports in a convenient position. A weight c is attached to the ends of the cords, sufficient to counterbalance the shield, which may thus be raised and lowered with entire ease by moving the weight 20 up or down. The shield is shown in full lines 25 in Figs. 1 and 2 in its elevated position, and in dotted lines s^2 in its lower position, in which it would be adapted to cover the coil to the bottom of the uptake E, and thus protect the coil from injury.

30 I am fully aware that it is not new to heat water and filter it before entering the boiler for the purpose of purifying it.

I am also aware that it is not new to arrange water-heating pipes in the uptake of 35 a return-flue boiler, as in United States Patent No. 369,697, dated September 13, 1887; but in such case the coil-pipes have been arranged upon the same level, so that the contents of one pipe would not drain automatically to the next, as in my construction. Furthermore, in the patent referred to the horizontal tier of pipes has been placed above the 40 return-flues and covered with a layer of non-combustible material placed permanently over the top of the coil, to prevent the hot smoke and gases from passing above such level. With a horizontal coil thus arranged it would be difficult, if not impossible, to apply a movable shield, as in my invention, and the vertical 45 arrangement of my coil, and the vertical arrangement of the inlet and outlet pipes i and m' enables me not only to secure a perfect discharge of the sediment from the pipes to a mud-drum located beneath the level of the 50 lowest pipe, but it enables me to apply a vertically-moving shield, which, owing to its vertical movement, may be readily counterbalanced by a falling weight, and may thus be arranged and held in the desired position 55 with the utmost facility. I therefore disclaim the said Patent No. 369,697, or the mere insertion of a heating-coil in the uptake of a boiler.

It is obvious that the pipe m' may be dif-

ferently arranged to permit the movement of 65 the shield vertically over the coil, as the discharge from the coil is beneath the lowest point to which the bottom of the shield would require to be moved.

Having thus set forth my invention, what 70 I claim herein is—

1. The combination, with the uptake of a flue-boiler, of the coil of pipes arranged vertically above one another and having suitable inlet and outlet pipes, and a shield movable vertically over the coil through an aperture in the boiler-casing, as and for the purpose set forth. 75

2. The combination, with the uptake of a flue-boiler, of the coil of pipes arranged vertically above one another, the vertical pipes i and m' , connected with the ends of the coil, the horizontal pipe j above the top of the boiler, the cocks l , n , and l' , inserted in the several pipes, and a shield movable vertically 80 over the coil and the pipes i and m' , as and for the purpose set forth. 85

3. The combination, with the uptake of a flue-boiler, of the coil of pipes arranged vertically above one another, the vertical pipes i and m' , connected with the ends of the coil, the horizontal pipe j above the top of the boiler, the mud-drum m at the junction of the coil and the pipe m' , the filter k , connected with the pipe j , and by pipe o with the boiler, 90 the cocks l , n , and l' , connected with the several pipes, and the shield movable vertically over the coil and the pipes i and m' , as and for the purpose set forth. 95

4. The combination, with the uptake of a flue-boiler, of the coil of pipes arranged vertically above one another, the vertical pipes i and m' , connected with the ends of the coil, the horizontal pipe j above the top of the boiler, the mud-drum m at the junction of the coil, and the pipe m' , the filter k , connected with the pipe j , and by pipe o with the boiler, the cocks l , n , and l' , connected with the several pipes, the shield movable vertically over the coil, as set forth, and suitable cords, pulleys, and weight to counterbalance the same, as and for the purpose set forth. 100 105 110

5. The combination, with the uptake of a flue-boiler, of the coil of pipes arranged vertically above one another and having suitable inlet and outlet pipes, and the shield consisting in the jackets s s' , connected together with the intermediate space t , and adapted to move vertically over the coil through an aperture 115 in the casing, as and for the purpose set forth. 120

In testimony whereof I have hereunto set my hand in the presence of two subscribing witnesses.

EMIL HOLTHAUSE.
